US0D1085124S

(12) **United States Design Patent** (10) **Patent No.:** **US D1,085,124 S**
(45) **Date of Patent:** **** Jul. 22, 2025**

(54) **DISPLAY SCREEN OR PORTION THEREOF
WITH GRAPHICAL USER INTERFACE**

(71) Applicant: **Matrix Absence Management, Inc.**,
Phoenix, AZ (US)

(72) Inventor: **Gordon Smith**, Phoenix, AZ (US)

(73) Assignee: **Matrix Absence Management, Inc.**,
Phoenix, AZ (US)

(**) Term: **15 Years**

(21) Appl. No.: **29/912,258**

(22) Filed: **Sep. 15, 2023**

Related U.S. Application Data

(63) Continuation of application No. 17/402,966, filed on Aug. 16, 2021, which is a continuation of application No. 16/858,462, filed on Apr. 24, 2020, now Pat. No. 11,093,902.

CLAIM

The ornamental design for a display screen or portion thereof with graphical user interface as shown and described.

DESCRIPTION

The FIGURE is a front view of a display screen or portion thereof with graphical user interface, showing the claimed design.

The hatching patterns depict a contrast in appearance.

(Continued)

The even-length broken lines illustrate a display screen or portion thereof and form no part of the claimed design.
